Primary Examiner—Antoine Duval Davis
Attorney, Agent, or Firm—Dority & Manning, P.A.[57] **CLAIM**

The ornamental design of a chuck, as shown and described.

DESCRIPTION

FIG. 1 is a perspective view of a chuck embodying the design of the present invention;
 FIG. 2 is a bottom view of the chuck illustrated in FIG. 1;
 FIG. 3 is a right side view of the chuck of FIG. 1;
 FIG. 4 is a left side view of the chuck of FIG. 1;
 FIG. 5 is a top view of the chuck of FIG. 1;
 FIG. 6 is a perspective view of a chuck embodying the design of the present invention;
 FIG. 7 is a bottom view of the chuck illustrated in FIG. 6;
 FIG. 8 is a right side view of the chuck of FIG. 6;
 FIG. 9 is a left side view of the chuck of FIG. 6; and,
 FIG. 10 is a top view of the chuck of FIG. 6.
 The chuck illustrated in FIGS. 1-5 is shaded for black and silver.
